CLAIM

The ornamental design for a base for a computer, computer terminal or similar article, as shown and described.

DESCRIPTION

FIG. 1 is a front perspective view of a base for a computer, computer terminal or similar article showing our new design;

FIG. 2 is a front elevational view thereof;

FIG. 3 is a top view plan thereof;

FIG. 4 is a right side elevational view thereof, the opposite side being a mirror image of the side shown; and

FIG. 5 is a rear elevational view thereof.

The broken lines are shown for illustrative purposes only.
